A new garden type *Chrysanthemum* plant named 'CIFZ0092' particularly distinguished by its medium size plant with mound plant habit, medium to large size daisy flowers, bicolor flower pattern with dark pink petal tips and cream yellow petal base and a natural season response early to mid-September.

1 Drawing Sheet**1**

Latin name of the genus and species of the plant claimed:
Chrysanthemum x morifolium.

Varietal denomination: 'CIFZ0092'.

BACKGROUND OF THE NEW PLANT

The present invention comprises a new *Chrysanthemum*, botanically known as *Chrysanthemum x morifolium*, and hereinafter referred to by the variety name 'CIFZ0092'.

'CIFZ0092' is a product of a planned breeding program. The new cultivar has medium size plant with mound plant habit, a medium to large size daisy flowers, bicolor flower pattern with dark pink petal tips and cream yellow petal base and a natural season response early to mid-September.

'CIFZ0092' originated from a cross made in December 2016 in Enkhuizen, The Netherlands. Seeds were sown in June 2017 in Gilroy, Calif. and 'CIFZ0092' was selected from the resulting population on Oct. 30, 2017 in Alva, Fla.

The female parent was the proprietary selection '13-M577', not patented.

15 The first act of asexual reproduction of 'CIFZ0092' was accomplished when vegetative cuttings were propagated from the initial selection in January 2018 in Alva, Fla.

BRIEF SUMMARY OF INVENTION

20 Horticultural examination of plants grown from cuttings of the plant initiated in January 2018 and continuing thereafter, has demonstrated that the combination of characteristics as herein disclosed for 'CIFZ0092' are firmly fixed and are retained through successive generations of asexual reproduction.

25 'CIFZ0092' has not been observed under all possible environmental conditions. The phenotype may vary significantly with variations in environment such as temperature, light intensity and day length.

30 A Plant Breeder's Right for this cultivar has not yet been applied for. 'CIFZ0092' has not been made publicly available prior to the effective filing date of this application, notwithstanding any disclosure that may have been made less than one year prior to the effective filing date of this application by the inventor or another who obtained 'CIFZ0092' directly from the inventor.

The following traits have been repeatedly observed and are determined to be basic characteristics of the new variety. The combination of these characteristics distinguishes this *Chrysanthemum* as a new and distinct variety.

BRIEF DESCRIPTION OF THE PHOTOGRAPHS

The accompanying photographic drawings show typical flower and foliage characteristics of 'CIFZ0092' with colors being as true as possible with an illustration of this type.

The photographic drawings show in FIG. 1 a close view of flower of the new variety and in

FIG. 2 a flowering plant from an outdoor trial.

The aforementioned photographs: FIG. 1, as well as FIG. 2 were taken on Sep. 8, 2021 both showing a plant from the same blackcloth outdoor trial in Enkhuizen, The Netherlands.

These plants were about 13 weeks of age. One rooted cutting per pot had been planted in a 19 cm pot, not pinched in week 23, 2021 and black clothed from week 29. Plants started flowering the end of August 2021.

The measurements were taken in Enkhuizen, The Netherlands, in September 2021 on plants from the same outdoor blackcloth trial.

Phyllaries:

Quantity.—20-23.

Color, upper surface.—RHS 138A.

Color, lower surface.—RHS 138A.

Length.—0.7 cm.

Width.—0.2 cm.

Shape.—Lanceolate.

Apex shape.—Acute.

Base.—Fused.

Margins.—Entire.

Texture, upper surface.—Glabrous.

Texture, lower surface.—Canescent.

Reproductive organs:

Pistil.—One.

Length.—0.5 cm.

Style color.—RHS 155C.

Style length.—0.3 cm.

Sigma color.—RHS 14C.

Sigma shape.—Bi-parted.

Ovary color.—RHS 157A.

Ovary length.—0.2 cm.

Ovary width.—0.1 cm.

Androecium:

Stamens.—1, found on only disc florets.

Color of filaments.—RHS 157C.

Length filaments.—0.2 cm.

Anther color.—RHS 14A.

Anther length.—0.2 cm.

Anther shape.—Oval to club shaped.

Color of pollen.—RHS 14A.

Pollen amount.—Moderate.

Fertility/seed set.—Has not been determined to date.

Disease/pest resistance.—Has not been determined to date.

Hardiness.—Has not been determined to date.

What is claimed is:

1. A new and distinct variety of *Chrysanthemum* plant named 'CIFZ0092' substantially as illustrated and described herein.
